(57) **CLAIM**

The ornamental design for a lanyard connector, as shown and described.

DESCRIPTION

FIG. 1 is a perspective view of a lanyard connector showing my new design;

FIG. 2 is a front view of the lanyard connector shown in FIG. 1;

FIG. 3 is a back view of the lanyard connector shown in FIG. 1;

FIG. 4 is a first side view of the lanyard connector shown in FIG. 1;

FIG. 5 is a second side view of the lanyard connector shown in FIG. 1;

FIG. 6 is a perspective view of a second embodiment of a lanyard connector showing my new design;

FIG. 7 is a front view of the lanyard connector shown in FIG. 6;

FIG. 8 is a back view of the lanyard connector shown in FIG. 6;

FIG. 9 is a first side view of the lanyard connector shown in FIG. 6;

FIG. 10 is a second side view of the lanyard connector shown in FIG. 6;

FIG. 11 is a perspective view of a third embodiment of a lanyard connector showing my new design;

FIG. 12 is a front view of the lanyard connector shown in FIG. 11;

FIG. 13 is a back view of the lanyard connector shown in FIG. 11;

FIG. 14 is a first side view of the lanyard connector shown in FIG. 11; and,

FIG. 15 is a second side view of the lanyard connector shown in FIG. 11.

The broken line showing of a lanyard and chord slide in FIGS. 6-10 and the broken lines extending from the bottom of the device holder in all of the drawing views is included for the purpose of illustrating environmental matter and forms no part of the claimed design.

1 Claim, 9 Drawing Sheets
